METHOD AND MEANS OF DISINTEGRATING
METAL INTO ABRASIVE MATERIAL

John F. Ervin, Ann Arbor, Mich.

Application October 14, 1940, Serial No. 361,158

10 Claims. (Cl. 83—91)

This invention relates to improvements in methods and means of shotting or disintegrating metal in the production of metal abrasive or the like discrete material, having reference to practice of the character described for example in my prior U. S. Patent No. 2,159,433 of May 23, 1939 upon which it is a further development.

The shotting of metal—sometimes called “atomizing”—is an operation involving certain technical difficulties arising from its nature and entirely satisfactory results have not yet been attained, especially when dealing with special metals or alloys in attempt to produce especially high quality abrasives. One of the principal difficulties is to secure a uniform shotting or comminution of the metal, so as to have the bulk of it formed into globules or spheroids of the same desired size and avoid the substantial loss or wastage from a breaking up into irregular fragment pieces and into mere pulverulent or dust. Another principal difficulty is to obtain a perfect globular or spherical formation of the shotted particles of metal broken up into discrete form, so as to avoid the loss of imperfect formations. Due to the forces existent in the break up of a metal into divided particles, it is hard to exercise any control upon the action taking place and what control is possible must be attained or imposed largely through the means and operative conditions provided for effecting the action.

An object of the invention is to provide an improved method and means of shotting metal, by which to attain a definite uniformity in size of the divided or comminute particles into which the same is broken up and to materially reduce the quantity and consequent loss of irregular disintegration with substantial amounts of waste fragment and mere pulverant.

Another object is to provide an improved method and means of the kind stated, by which to obtain a true spherical formation of the divided metal particles and to substantially reduce if not to wholly eliminate the possibility of imperfect formations necessary to be separated out, with consequent loss.

A further object is to provide such a method and means by which to control within substantial limits the size of the shotting or breaking of the metal into granular particles or globules.

The invention will be more particularly described by the following specification with reference to the accompanying drawings, illustrating the same in two exemplary working embodiments of alternative or different modification plan represented in elementary form.

In said drawings:

Fig. 1 is a side elevation view in part section of one embodiment;

Fig. 2 is a top plan view of Fig. 1, omitting the receptacle member thereabove;

Fig. 3 is a detail front end view looking from the left of Fig. 2;

Fig. 4 is a side elevation view in part section of the other embodiment;

Fig. 5 is a top plan view of Fig. 4, omitting the upper receptacle member;

Fig. 6 is a detail view taken on the line 6—6 of Fig. 4; and

Fig. 7 is a broken off view illustrating a detail of modification.

The claimed invention consists fundamentally in discharging a molten stream of the metal into the angle between two convergently meeting streams of liquid, said liquid streams being projected under regulated variable pressure force and in the form of a closely spaced series of fine streams or jets.

In the embodiment or arrangement of Figs. 1 to 3, one of the liquid streams, designated as 10, is employed as the main stream and is projected in a horizontal plane. The other stream 11 constitutes the secondary stream and is projected in a substantially vertical plane. The metal in a molten stream 12 is discharged into the angle formed between these two converging streams, in this instance onto the main stream slightly in advance of the secondary stream's contact therewith. This secondary stream is adapted to be swung toward and away from the point of the metal stream contact with said main stream, thereby increasing or decreasing the angle between the two liquid streams, so as to quicken or delay its action upon the metal stream.

The two liquid streams are projected in a closely spaced series of fine streams or jets 10^a and 11^a respectively, the former through nozzle orifices 13^a in a nozzle head 13 and the latter through nozzle orifices 14^a in a nozzle head 14. The main stream jets 10^a collectively form a relatively thick bodied spout of the liquid by arrangement of the nozzle holes 13^a in tiers one above another (see Fig. 3) and will advantageously give a cross-sectionally trough shape to said spout or stream by arranging the rows in the form of a V or U as shown in the front detail view. The secondary stream jets 11^a collectively form a substantial sheet or curtain of the liquid by arrangement of the nozzle holes 14^a in a straight line (see Fig. 3) or by disposal in staggered relation as represented for example in Fig. 7. It should here be stated

that the two liquid streams have been represented in parallel shafts to indicate their composition by multiple individual jets or separate fine streams spaced closely together.

The main stream 10 is projected through said nozzle head 13 carried on the end of a nozzle arm or tube 15, the latter being swivel connected with a supply pipe 16 through which the liquid is supplied under pressure from a suitable supply source (not shown) and having a control valve 17 therein for regulating the force of the supply therethrough. The swivel connection with said supply pipe is advantageously of a compound or universal type so as to permit its swing in both vertical and horizontal planes, although a swivel to swing in a vertical plane only will in most cases be sufficient. The connection for vertical swing may be provided for example by a nipple 18 carried by a collar 18a rotatable on the supply pipe 16 so as to swivel the nozzle upon the axis of said supply pipe, while the connection for horizontal swing may be provided for example by a neck or T-coupling 19 fitting into and rotatable within said nipple so as to swivel the nozzle upon the axis of said nipple (see the arrows indicating the nozzle swing in the two planes). The forward end of the nozzle is supported by a stirrup bar 20 adjustable up and down by a worm wheel 21 working on its suspension shaft 20a from a suitable fixture bracket. Thus, it will be firmly supported in any position to which it is set.

The secondary stream 11 is projected through said nozzle head 14 comprising or connected to the end of a supply pipe (not shown) through which the liquid is supplied under pressure from a suitable source (not shown). This nozzle 14 is rotatable in opposite directions upon its own axis, as indicated by the arrows, so as to swing the said secondary stream toward and away from the point of metal stream contact with the main liquid stream as previously stated. Suitable provision is of course made to hold said nozzle in the position to which it is set or adjusted.

The metal stream is supplied through a vat 22 located above the main stream level and having a trough or nozzle 23 from which the molten metal supplied from said vat is discharged onto the main liquid stream as stated. This molten metal stream may be discharged or projected under pressure rather than by gravity alone, if so desired, by provision made therefor within the vat and said drain or nozzle 23 of course determines the size or thickness of the stream which is projected.

Referring to Fig. 3, an additional nozzle 13 is represented in dotted lines at the left of the single nozzle shown in full lines. This representation is made to indicate how a series of corresponding nozzles might be laid out in horizontal adjacency either to widen the breadth of the main stream or to provide a series of main streams to act upon a corresponding series of metal streams caused to discharge from the vat 22. In the event of such addition or provision of added nozzles, the secondary stream 11 may be correspondingly widened by simply adding an additional number of nozzle orifices 14a to the line thereof. Such a modification will be obvious in the light of what has been heretofore described and will require no further description or amplification.

In the embodiment or arrangement of Figs. 4 to 6, the two liquid streams, designated 100 and 111, are projected in oppositely inclined planes toward a common center. The molten metal

stream 12 is in this instance discharged directly into the vortex of these meeting streams so as to be acted upon alike or at the same time by both.

The said two liquid streams are projected from 5 parallel nozzle heads 133 and 144 through nozzle apertures 133a and 144a in a closely spaced series of fine streams or jets 100a and 111a respectively, as in the first described embodiment. Said nozzle apertures are formed in the nozzle heads in a 10 straight longitudinal line in this instance, although they might be arranged in staggered relation or in staggered rows as represented in Fig. 7. In other words, the body thickness of the streams will be determined not only by the size and closeness of said apertures, but by the number of rows 15 in which they are formed in the said nozzle heads. The primary consideration is to make them form or produce streams of sufficient thickness to act with proper force and to the proper extent upon 20 the molten metal.

Said nozzle heads 133 and 144 are mounted to 25 swing parallel to each other in a vertical plane at the end of the nozzle arm or tube 15, as indicated by the arrows, in order to change the angle 30 of their action upon the metal stream, as well as the distance to be traversed by the metal stream before contacting the same. In other words, said nozzle heads are arranged to swing up and down substantially upon the arc described by the metal stream from its projection point, thereby quickening or delaying the latter's contact with the liquid streams. This swinging or swivel connection is effected as by a pipe piece 24 rotatable within a 35 T-coupling 25 on the nozzle tube end and to 40 which said nozzle heads are connected by elbows 26. Said nozzle heads are also individually turnable upon their own axes as indicated in Fig. 6, thereby permitting them to be adjusted so as to change the angle at which the two liquid streams 45 are brought together. Referring to Fig. 6, the angle at which the two streams are in this instance brought together is indicated in full lines and by the letter *a*. Other angles, both greater and smaller, at which they may be adjusted to 50 meet are indicated in dotted lines by the letters *b* and *c*. Thus, the depth of the vortex or angle into which the metal stream is discharged against the liquid streams may be regulated according to wish or result requirements. Ordinarily, the best 55 angle of the liquid streams' meeting will be approximately that indicated in the full lines in this and the other views, as otherwise the action or agitation between the two liquid streams themselves may be too great or too little.

Said nozzle arm or tube 15 in this instance supplies both of the parallel nozzle heads and is connected with a suitable source of liquid supply under pressure as before described. That is to say, said nozzle arm or tube is connected with the 60 supply pipe 16 and is provided with a control valve 17 for regulating the force of the liquid supply therethrough. In this instance, only the neck or T-coupling 19 is shown in its connection with the supply pipe 16, but it will be understood 65 that the connection is or will be the same as described in the first embodiment, so that said nozzle pipe may be adjustably swung in both vertical and horizontal planes. Also, as in the first instance, said pipe is supported by an adjustable stirrup bar 20 at its forward end. The metal stream is discharged as before from the 70 vat 22 and trough or nozzle 23.

In operation, the liquid streams are projected 75 under pressure ranging from approximately 30 to 120 pounds per square inch, giving them a

substantial flow force. In the first embodiment, the secondary stream 11 is maintained at a pressure force somewhat less than that of the main stream 10. In the second embodiment, however, both are maintained at the same pressure force. This pressure can be regulated at the source and by the valve 17 controlling the main stream in the first embodiment and both streams in the second embodiment. Of course a like control may be provided for the secondary stream, although it is not herein shown. The pressure is regulated to a degree at which the desired disintegration, or the disintegration into the desired size of particles will be produced and it may of course be varied according to the intended degree of shooting or working conditions.

In this, a number of factors are to be taken into consideration: First, the pressure or gravity force with which the molten metal is discharged and the size of the stream in which the discharge is made. Second, the distance from the point of metal projection at which contact with the liquid streams, or either of the same, takes place. Third, the pressure of the two liquid streams or, in the case of the first embodiment, the pressure at which one is maintained in relation to the other. Fourth, the fineness of the individual streams or jets of each component stream and the extent to which said individual streams maintain their individuality or separation from each other in the projection from their nozzles. Fifth, the fineness or degree of the shooting to be produced, i. e. the size of the particles or globules into which the molten metal is to be transformed into granular material. Sixth, the degree or extent of disturbance or agitation caused by contact of the hot molten metal stream with the colder, though possibly heated, liquid streams. Seventh, the character of the liquid streams and whether they are or are not of oily content such as oil emulsions or the like.

All of the above factors must be taken into consideration because they have an effect upon the result produced. Generally speaking, the smaller the size or thickness of the metal stream, the smaller will be the degree of liquid stream pressure necessary to disintegrate it into the desired particles, or vice versa. Likewise, the greater the distance at which the metal stream contacts the liquid streams from its point of projection, the more severe the disturbance or agitation between the two will be, due to the accelerative effect of gravity, and vice versa. Further, the more refined or small the individual streams or jets of the two main streams are, the more finely will they tend to break up the molten metal stream with which they are brought into contact, and vice versa. Again, a hard liquid will of course be more harsh in its action upon the metal than a soft or oily liquid would be. Finally, the greater the pressure of the liquid streams, the more fine or minutely will they tend to break up the molten metal stream. These various factors must be and are taken into consideration and adjustments made accordingly, depending upon the character of the results or resulting product to be produced. It is simply a matter of regulation and adjustment to suit the various conditions and requirements.

The liquid streams coming into contact with the molten metal stream instantly disintegrate or break it up into small particles. This break-up is definitely and predominately uniform because of the uniformity in size of the individual jets or streams composing the two liquid streams and

through or between which the broken particles must pass while being carried forward by the force of the stream flow. In the case of the first embodiment, the main stream effects an initial break-up which is followed by the secondary stream adding to its effect and completing what disintegration may not initially take place. In the case of the second embodiment, the combined liquid streams acting upon the metal in the vortex of their meeting produce the same effect, except that it is a little more uniform and causes a somewhat finer disintegration. The disintegrated particles of the metal are rolled upon and between the individual streams or jets of the two liquid streams as they are carried forward from the contact point and so gives or forces them into a perfectly spherical or globular formation. The whole action takes place under the predominate force or pressure flow of the liquid streams over that of the metal stream and the result is somewhat better and more satisfactory if the liquid is composed of an oil emulsion so as to be smooth and more gentle in its action upon the metal than hard liquid like water would be. It is desirable also for the liquid to be heated or warmed to an extent that will reduce its cooling or quenching effect upon the metal. This will also tend to reduce the disturbance or agitation occurring at the point where the metal and liquid streams come together.

The entire operation takes place within an enclosing chamber (not shown) such as shown for example in my aforementioned prior Patent No. 2,159,433, in connection with which provision is made to exclude air and gases so that the shooting action can take place within the desired medium or atmospheric surrounding and under conditions which will not be variable. The disintegrated particles of the metal thus broken up into globules of the desired size are dropped into a quenching pool (not shown) of liquid in the bottom of said chamber where they are further quenched and cooled to the point of complete hardening, so that they can be removed, dried and properly treated for commercial use.

The advantages of this method of disintegrating or shooting metal will undoubtedly be appreciated. It provides an operation attaining decidedly superior results, not only in the character of the product recovered from the metal, but in the saving of wastage or fragmentary, incomplete and purely blastic disintegration. A very much higher proportion of perfect shooting in usable form—amounting to as much as 25% more in marketable sizes—is obtained and a greater uniformity of size in the resultant particles is realized. Materially reducing as it does the loss of wastage from irregular, fragmentary or mere pulverizing disintegration, it is more economic. Moreover, the means employed for the practice of this method in either of the plans or arrangements described lends flexibility to this system in that the liquid system discharges hinge about swivel centers permitting them to be swung or adjusted to different angular positions or relationships to the metal stream. Thus, the focal or most effective point of the liquid streams can be brought into play against the metal stream so that their component multiple disintegrating fine streams or jets can be brought into play thereagainst, or adjusted otherwise to modifiably produce the desired degree of disintegration. The whole system is of course subject to regulation, adjustment and control according to the results desired.

It will be understood that various modifications or various changes can be made in the application of the method and in the means for carrying the same into practice. Therefore, it will be appreciated that the invention is not limited to the specific plan or arrangement nor to the specific form or relation shown and described. Hence, the appended claims are not intended to limit the invention in any way beyond what said claims by their own terms of definition expressly impose.

Having thus described my invention, what I claim as new, and desire to secure by Letters Patent of the United States is:

1. The method of disintegrating metal into globular abrasive material, which consists in discharging a molten stream of the metal into the angle formed between multiple convergently meeting streams of liquid adjacent the line of intersection of said liquid streams, each liquid stream being projected under regulated variable pressure in the form of closely spaced series of solid pencil-like jets, between, through and around which the molten stream passes, shattering the same, thereby uniformly dividing said molten stream into drops which solidify into substantially round shape due to their surface tension.

2. The method of disintegrating metal into globular abrasive material, which consists in discharging a molten stream of the metal into the angle formed between two streams of liquid projected convergently toward a common center, said molten stream impinging adjacent the line of intersection of said liquid streams, each liquid stream being projected under regulated variable pressure in the form of multiple closely spaced solid pencil-like jets maintained separate at least to the point of contact with the metal stream, and between, through and around which jets the molten stream passes, shattering the same, thereby uniformly dividing said molten stream into drops which solidify into substantially round shape due to their surface tension.

3. The method of disintegrating metal into globular abrasive material, which consists in discharging a molten stream of the metal into the angle formed between two streams of liquid projected convergently toward a common line of intersection, said molten stream being contacted with one of said liquid streams in advance of the other within said angle, each liquid stream being projected under regulated variable pressure force in the form of closely spaced series of solid pencil-like jets, between, through and around which the molten stream passes, shattering the same, thereby uniformly dividing said molten stream into drops which solidify into substantially round shape due to their surface tension.

4. The method of disintegrating metal into globular abrasive material, which consists in discharging a molten stream of the metal into the angle formed between two streams of liquid projected convergently toward a common line of intersection, said molten metal being projected directly into the line of intersection of said liquid streams so as to contact both simultaneously, each liquid stream being projected under regulated variable pressure in the form of closely spaced series of solid pencil-like jets, between, through and around which the molten stream passes, shattering the same, thereby uniformly dividing said molten stream into drops which solidify into sub-

stantially round shape due to their surface tension.

5. The method of disintegrating metal into globular abrasive material, which consists in discharging a molten stream of the metal into the angle formed between two streams of liquid projected convergently toward a common line of intersection, said metal stream being contacted with one of said liquid streams somewhat in advance of the other within said angle, each liquid stream being projected and maintained under regulated variable pressure in the form of multiple closely spaced solid pencil-like jets; one of said liquid streams being trough-shaped and the other being in the form of a sheet, between, through and around which liquid streams the molten stream passes, shattering the same, thereby uniformly dividing said molten stream into drops which solidify into substantially round shape due to their surface tension.

6. The method of disintegrating metal into globular abrasive material, which consists in discharging a molten stream of the metal into the angle formed between two streams of liquid projected convergently toward a common line of intersection, said metal stream being projected directly into the line of intersection of said liquid streams so as to contact both simultaneously, each liquid stream being projected under regulated variable pressure in the form of closely spaced series of solid pencil-like jets forming a sheet or curtain, between, through and around which the molten stream passes, shattering the same, thereby uniformly dividing said molten stream into drops which solidify into substantially round shape due to their surface tension.

7. Means for disintegrating metal into globular abrasive material, comprising in combination with a suitable enclosing chamber, means for projecting a molten stream of the metal from a supply source, means for convergently projecting two streams of liquid towards a common line of intersection into which said projected metal stream discharges, means for adjusting said liquid streams to vary the angle therebetween, and means for projecting each liquid stream under regulatory variable pressure force in the form of multiple closely spaced series of solid pencil-like jets, between, through and around which the molten stream passes.

8. Means for disintegrating metal into globular abrasive material, comprising in combination with a suitable enclosing chamber, means for projecting a molten stream of the metal from a supply source, means for separately projecting two streams of liquid convergently toward a common center in front of said metal stream so that the former will discharge into the angle formed between the two, means projecting said liquid streams in the form of multiple closely spaced series of solid pencil-like jets under regulatable variable pressure between, through and around which the molten stream passes, and means for adjustably swinging said liquid streams to vary the angle between the two.

9. Means for disintegrating metal into globular abrasive material, comprising in combination with a suitable enclosing chamber, means for projecting a molten stream of the metal from a supply source, means for separately projecting two streams of liquid convergently toward a common center in front of said metal stream so that the molten stream will discharge into the angle between the two, means in the projection of said liquid streams for dividing them respectively into

a multiple of closely spaced solid pencil-like jets composing the same through, between and around which the molten stream passes, means supplying said liquid streams under pressure force from a suitable source together with means for regulating the pressure of said supply, and means for separately adjustably swinging said liquid streams so as to vary or change the angle between the two.

10. The method of disintegrating metal into 10.

globular abrasive material which consists in discharging a stream of molten metal into a closely spaced series of solid pencil-like liquid jets between, through and around which the molten stream passes, shattering same, thereby uniformly dividing said molten stream into drops which solidify into substantially round shape due to surface tension.

JOHN F. ERVIN.
